MOP WRINGER

William L. Chew, Rockville Centre, N. Y.

Application June 10, 1935, Serial No. 25,922

13 Claims. (Cl. 15—261)

The invention relates to a mop wringer.

The object of the present invention is to improve the construction of mop wringers by doing away with operating members, such as hand levers or foot levers, and to provide a simple, practical and efficient mop wringer of strong, durable and comparatively inexpensive construction adapted to be operated solely by the pressure of a mop introduced into the mop wringer for causing mop squeezing members to compress the mop and squeeze water out of the same.

A further object of the invention is to provide a mop wringer of this character capable, after being operated to squeeze water out of a mop, of opening automatically when relieved of pressure so that the mop may be readily removed from the wringer, and the latter arranged for subsequent use.

With these and other objects in view, the invention consists in the construction and novel combination and arrangement of parts herein-after fully described, illustrated in the accompanying drawings and pointed out in the claims hereto appended, it being understood that various changes in the form, proportions and minor details of construction may be resorted to without departing from the spirit or sacrificing any of the advantages of the invention.

In the drawings:

Figure 1 is a perspective view of a mop wringer constructed in accordance with this invention.

Figure 2 is a transverse sectional view of the same showing the mop wringer mounted upon a receptacle, the mop squeezing leaves being in their open position.

Figure 3 is a similar view, the mop squeezing leaves being in their closed position.

Figure 4 is a central vertical sectional view taken longitudinally of the mop wringer.

Figure 5 is a detail perspective view of the mop squeezing leaves and the crosshead member.

Figure 6 is a detail end view of a portion of the mop wringer illustrating the arrangement of the links.

In the accompanying drawings, in which is illustrated the preferred embodiment of the invention, the mop wringer comprises in its construction a casing or housing 1 constituting a support for the mop wringing mechanism and composed of an outer imperforate side wall 2 and end walls 3, the housing or casing being open at the top, bottom and inner side. The end walls 3 are preferably provided with a slight downward taper and they are connected at the top and bot-

tom at the opening in the side of the housing by upper and lower horizontal connecting bars 4 and 5. The housing may be constructed of metal and consist of a casting but any suitable material may, of course, be employed in the construction of the housing. The end walls are provided with apertures preferably consisting of curved slits 6 and the partially severed metal is preferably deflected slightly to provide a shield at each aperture to prevent water passing through the apertures from splashing upwardly.

The housing is designed to be mounted on the upper edge of a tub, bucket or analogous receptacle and it is provided at its outer side with recesses 7 which receive the upper edge of the receptacle 8. The lower connecting bar 5 is provided at its terminals with extended claws 9 adapted to engage the upper edge of the receptacle and in order to firmly maintain the wringer in its position upon the receptacle the housing is provided at the outer side with legs 10 extending downwardly and outwardly from the outer side wall 2 and designed to be of a length to rest upon the floor or other surface upon which the receptacle 8 may be placed. The legs 10 are preferably curved as shown and the mop wringer when in use extends inwardly over the receptacle so that water squeezed from a mop will flow into the receptacle.

Within the housing is arranged a pair of substantially rectangular mop squeezing leaves 11 constructed of suitable metal and arranged in an upright position and provided at their lower edges with aligned eyes 12 through which passes a horizontal pintle 13 of a vertically slideable cross-head member 14. The mop squeezing leaves are provided at their upper edges with rods 15 projecting beyond the side edges of the leaves 11 and arranged in transversely disposed guide slots 16 formed in the end walls 3 of the housing adjacent the upper edges thereof. The guide slots 16 which are preferably horizontal terminate short of the center of the upper portions of the said side walls 3 and the end portions of the rods 15 project through the guide slots 16 and are connected by links 17 to the upper ends 18 of vertical rods 19 constituting slides for the crosshead member and guided in vertical openings 20 of webs or flanges 21 of the end walls of the housing. The upper ends 18 of the rods 19 are bent at right angles and they form pivots for the links 17 which extend upwardly and outwardly from the upper ends of the rods 19 to the projecting portions 22 of the rods 15. The links 17 are provided at their ends with suitable eyes 23 and 24

to receive the ends 18 of the rods 19 and the terminals 22 of the rods 15. The eyes 24 are elongated or in the form of slots to permit the necessary play of the pivotal connection between 5 the links and the upper ends of the mop squeezing leaves.

The crosshead member 14 is composed of an inverted U-shaped mop receiving loop 25 forming an open frame and connected at its ends 10 with the horizontal pintle 13. The inverted U-shaped loop which is located between the mop squeezing leaves is also connected by lower approximately U-shaped portions or bends 26 with the lower ends of the rods 19. The rods 19 are 15 located exteriorly of the end walls 3 and the bends 26 extend beneath the end walls and are formed integral with the inverted U-shaped loop and the horizontal pintle 13. The webs or flanges 21 preferably extend across the lower ends of 20 the side walls 3 and guide the slides 19 in the upward and downward movement of the crosshead member 14. The loop portion 25 of the crosshead member 14 is arranged interiorly of 25 the housing and between the leaves 11 in position to be engaged by the head of a mop which is adapted by downward pressure to move the crosshead member downwardly and thereby move the leaves inwardly to squeeze the mop and express water from the same. The mop engaged 30 loop 25 is of a size to extend to the upper portions of the leaves so that the major portion of the surfaces of the leaves will operate on a mop head for squeezing the same.

After the mop wringer has been operated by 35 a mop to squeeze the water from the mop head, the leaves 11 are automatically opened when the loop 25 is relieved of pressure in withdrawing the mop from the wringer. This automatic opening of the leaves is effected by springs 27 having 40 coils 28 disposed on the terminal pivot portions 18 of the slides 19. The ends 29 of the springs are bent around or otherwise engaged with the links 17 for swinging the same outwardly to move the projecting guided portions of the leaves outwardly in the guide slots 16. The downward 45 movement of the crosshead member carries the guided portions 22 of the leaves inwardly and the upward movement of the crosshead member and the outward movement of the links 17 move the 50 said guided portions 22 outwardly for opening the mop squeezing leaves.

The lower portions of the mop squeezing leaves are preferably provided with corrugations 30 substantially the same as those of an ordinary 55 washboard and the said leaves are provided at intervals with apertures 31 preferably formed by curved slits which provide shields 32 above the apertures to prevent upward splashing of water passing through the apertures. Also the leaves 60 are provided at their side edges with recesses 33 located adjacent the lower edges of the leaves which enable the leaves to clear the lower ends of the sides of the mop engaged loop 25 so that the latter may occupy a position between the 65 leaves without interfering with substantial closing of the leaves on a mop head.

What is claimed is:

1. A mop wringer including a pair of mop squeezing leaves, means for mounting the leaves for relative inward and outward movement to open and close the leaves, and means connected with the leaves and extending to a point between the upper and lower ends of the leaves and arranged to be directly engaged by a mop head when the same is introduced between the 70

leaves, said means being operable by the pressure of a mop for moving the leaves with respect to the said means for closing the leaves to squeeze the mop.

2. A mop wringer including a pair of mop squeezing leaves, means for mounting the leaves for relative movement toward and from each other to open and close the leaves, and means connected with the leaves and extending between the same from their point of connection with each other to a point between the upper and lower ends of the leaves and arranged to be directly engaged by a mop inserted between the leaves and operable by pressure of a mop for moving the leaves toward each other to squeeze 15 water from the mop.

3. A mop wringer including a pair of opposite mop squeezing leaves hinged together at two adjacent edges for relative movement toward and from each other, and means connected with the 20 leaves at their point of connection with each other and extending to a point between the upper and lower ends of the leaves and arranged to be directly engaged by a mop inserted between said leaves, said means being actuated by pressure of 25 a mop for moving the leaves toward each other to squeeze the mop and express water therefrom.

4. A mop wringer including a pair of opposite mop squeezing leaves hinged together at their lower ends for relative inward and outward movement to close and open the leaves, and means connected with the leaves and having a mop receiving portion located between the leaves and above and in spaced relation to the point of hinging of the leaves and actuated by pressure of 30 a mop for moving the leaves inwardly toward said mop receiving portion to squeeze the mop.

5. A mop wringer including a support, a crosshead member guided on the support and movable upwardly and downwardly and having a 40 mop receiving portion arranged to be engaged by a mop and to move downwardly under pressure of the same, a pair of mop squeezing leaves mounted on the crosshead member below and in spaced relation to said mop receiving portion 45 for relative inward and outward movement toward and from the mop receiving portion of the crosshead member, and means for connecting the crosshead member with the leaves for moving the same inwardly when the crosshead member 50 is moved downwardly.

6. A mop wringer including a support having transverse guiding means at its upper portion and vertical guiding means at its lower portion, a crosshead member mounted in the vertical 55 guiding means and movable upwardly and downwardly and provided with a mop receiving portion, a pair of mop squeezing leaves hinged to the crosshead member below and in spaced relation with the mop receiving portion thereof and 60 carried by the crosshead member and having portions guided in the transverse guiding means of the support, and means for connecting the crosshead member with the guided portions of the leaves for moving the leaves inwardly toward 65 said mop receiving portion when the crosshead member is moved downwardly.

7. A mop wringer including a housing comprising an outer side wall and end walls and open at the inner side, a vertically movable 70 crosshead member having portions arranged interiorly and exteriorly of the housing and provided exteriorly thereof with a mop receiving portion, means for guiding the exteriorly arranged portions of the crosshead member for up- 75

- ward and downward movement of the latter, a pair of mop squeezing leaves arranged within the housing at opposite sides of said mop receiving portion and hinged at the bottom to the cross-head member in spaced relation to the mop receiving portion to move toward and from said mop receiving portion, and means for connecting the exterior portions of the crosshead member with the leaves for moving the latter inwardly when the crosshead member moves downwardly.
8. A mop wringer including a housing, a vertically movable crosshead member comprising an open frame located within the housing and having a mop receiving portion at the top thereof and provided with a horizontal pintle and vertical slides arranged exteriorly of the housing and connected with the said open frame at the bottom thereof, means carried by the housing for guiding the slides in the vertical movement of the crosshead member, mop squeezing leaves located at opposite sides of the open frame of the crosshead member and hinged together at their lower edges by the said pintle for movement toward and from the mop receiving portion of the crosshead member, and links connecting the upper portions of the slides with the upper portions of the leaves for moving the leaves outwardly when the crosshead member is moved upwardly, said crosshead member being moved downwardly by pressure of a mop against the mop receiving portion of the said open frame of the crosshead member to move the mop squeezing leaves inwardly.
9. A mop wringer including a housing provided in its upper portion with substantially horizontal slots, a vertically movable crosshead member having portions arranged interiorly and exteriorly of the housing and having a mop receiving portion interiorly of the housing, mop squeezing leaves arranged within the housing at opposite sides of the interiorly arranged mop receiving portion of the crosshead member and hinged at their lower portions to the latter below and in spaced relation to said mop receiving portion for movement toward and from the mop receiving portion and having rods at their upper portions extending through the slots of the housing, means carried by the housing for guiding the exterior portions of the crosshead member, links connecting the exterior portions of the crosshead member with the extended ends of the said rods for moving the latter and the leaves outwardly when the crosshead member is moved upwardly, said leaves being moved inwardly when the crosshead member is moved downwardly by pressure of a mop upon its interiorly arranged mop receiving portion, and springs operatively connected with the links for moving the same outwardly to open the leaves when the pressure of the mop is removed from the crosshead member.
10. A mop wringer including a casing, a pair of mop squeezing leaves located within the casing and hinged together at their lower ends for movement toward and from each other, and a mop actuated member slidably mounted on the casing and connected with the mop squeezing leaves for moving the same inwardly when the mop actuated member is moved downwardly by pressure of a mop, said mop actuated member being provided with a mop receiving portion located between the leaves at a point above and in spaced relation with the hinged lower ends thereof in position to be engaged by a mop head when the same is inserted between the leaves.
11. A mop wringer including a housing open at the top, bottom and inner side and having im-perforate end walls and an imperforate outer side wall, legs extending downwardly from the housing at the outer side wall thereof and located adjacent the end walls and provided at their upper portions with notches located at the inner edges of the legs for the reception of the upper edge of a receptacle to permit the housing to be arranged over the receptacle with the legs disposed exteriorly thereof, and rigid arms extending outwardly from the end walls adjacent the open side of the housing and provided at their outer ends with claws arranged to engage the upper edge of said receptacle and mop squeezing mechanism contained within the housing.
12. A mop wringer including squeezing ele- ments arranged to move toward and from each other, a movably mounted member having a limited movement in two directions and operatively connected with the mop squeezing elements for moving the same toward each other to squeeze a mop when the said member is moved in one of said directions by pressure of the mop, said member including a mop receiving portion extending between the mop squeezing elements to a point between the ends thereof and arranged to be engaged by a mop, and means for automatically moving the member in the other of said directions and the mop squeezing elements away from each other when the said member is relieved of pressure.
13. A mop wringer including a mop actuated member movable upwardly and downwardly and having a portion arranged to be engaged by a mop for moving the said member downwardly, mop squeezing leaves located at opposite sides of the mop engaged portion of the said member, and means spaced from said mop engaged portion for connecting the said member with the leaves for moving the latter inwardly towards each other to squeeze a mop when the same forces the said member downwardly, and means for automatically moving the mop actuated member upwardly and the leaves outwardly when the said member is relieved of the pressure of the mop.
